Attorney

UNITED STATES PATENT OFFICE.

JOHN FRICK, OF DETROIT, MICHIGAN.

CUP-DISPENSING APPARATUS.

Original application filed July 23, 1919, Serial No. 312,806. Divided and this application filed February 20, 1922. Serial No. 537,797.

This invention relates to an improvement in cup dispensing apparatus and more particularly for dispensing nested paper cups.

A large portion of the paper cups used to-day at soda fountains, or which are dispensed in railroad cars, stations, or at drinking fountains, are of conical form, and are provided with an annular flange at their larger end or the top thereof. These cups are usually nested in a container or dispensing device, and are removed one by one as they are to be used. As the taper of these cups is usually of a very slight angle, the cup to be removed frequently sticks to the next cup to such an extent that the delivery mechanism will frequently miss delivering a cup when it is actuated.

The object of my invention is to provide dispensing mechanism which is so arranged and actuated as to insure the delivery of a cup for each actuation, so long as there is a supply of cups in the container.

I accomplish this object by providing a plurality of holders and ejectors, preferably three, which are arranged to engage the flange of the second cup to restrain said cup against movement, and to simultaneously engage, at a plurality of points, the flange of the cup to be ejected, and move the cup parallel to the axis of the cups to prevent jamming or locking of the first cup within the second cup.

Another object of my invention is to provide devices of this character which will engage the flanges of the cups at points close to the junction of the body and flange of the cup, as well as device which will engage a large area of the flange, to distribute the pressure exerted thereon over a relatively large surface.

The precise nature of my invention will be best understood by reference to the accompanying drawings, which will now be described, it being premised, however, that changes may be made in the details of construction without departing from the spirit and scope of my invention as defined in the appended claims.

Figure 1 is a plan view of one form of cup holding and delivery mechanism, built in accordance with my invention.

Figure 2 is a sectional view on the line 2—2, of Fig. 1.

Figure 3 is a similar view on the line 3—3 of Fig. 1.

Figure 4 is a detail bottom view of one pair of the cup holding fingers and their carrying slides.

Figs. 5, 6 and 7, perspective views showing respectively the upper and lower fingers, 60 the ejectors, and their actuating devices, in their several positions.

In these drawings, the reference character 36 designates a cylindrical container which is partially cut away to permit the insertion 65 of a stack of nested paper cups 37. The container 36 is supported within an annular flange 38 on a base member 39, which may be supported in any desired manner within a suitable case or cabinet. 70

The nested cups are supported in an upright position by means of suitable fingers, which are in engagement with either the annular flange 40 on the lower cup, or a similar flange on the next to the lowest 75 cup when the lowest cup is being ejected.

Slidably mounted for radial movement in guides formed in the base plate 39 and angle plates 42 secured thereto, are lower and upper cup supporting fingers 41 and 45, respectively, and which are moved to their retracted positions by the springs 43 and 47, respectively.

44 and 48 are cam rings in an annular seat in the base plate 39, and are each provided with three recesses and three high points, for actuating the three fingers 41 and 45 of the two sets through the medium of rollers 41^a, 45^a, on said fingers, and are retained in engagement with the cams by 90 means of the springs 43 and 47. The rollers 41^a are shown in Figs. 2 and 3, the rollers 45^a being shown in full lines in Figs. 2 and 4 and in dotted lines in Fig. 1.

49 are ejector levers there being one 95 mounted on each of the lower fingers 41 on a pin 50, and are arranged to be moved radially with said fingers. Each ejector lever is provided with an extension 51, having projections between which is mounted a 100 roller 52. 53 are cams on the cam ring 48, which are arranged to pass under rollers 52 when the cam rings are rotated as hereinafter described, to rock the ejectors 49 and eject the lowermost cup 37. 105

The cam rings 44 and 48 are secured to each other by means of screws 65, and 61 is an operating handle secured to the top cam ring 48 and is normally held against a stop plate 63, by springs 54. These springs 110

54 are connected to pins on the upper cam ring 48 and pins on the base 39.

Pivoted to the base 39 is a locking lever 55 which is normally held in the position shown in Figure 1 by a spring 57, so that the end thereof is within a low point in the cam ring 44 and prevents shoulder 66 passing beyond the lever 55, unless the lever is first withdrawn, as hereinafter described.

10 56 is a cam face on the lever 55, in line with the edge of coin 58 when inserted in a slot in the hand lever 61.

Connected at one end to the base 39, is a plate 59 having ratchet teeth 60 at the other end thereof, and which plate extends along the line of movement of the coin in the slot in the hand lever 61, for supporting the coin 58, through the major portion of the movement of the coin.

20 67 is a coin chute extending from the annular flange 38 to the wall of the casing and is arranged to deliver the inserted coin to the slot in the hand lever 61.

The parts are normally in the position shown in the drawings and in which the fingers 45 and their ejecting levers are retracted to points beyond the flanges 40 of the cups 37, and the rest of cups is supported by the fingers 41 which are advanced under the flange 40 of the lowermost cup.

When it is desired to eject a cup, a coin is inserted in the chute 67, which will pass into the slot in the hand lever 61, as shown in Figs. 1, 2 and 3.

35 The hand lever 61 is now moved clockwise and during its first movement the coin will ride along the cam face 56 on locking lever 55 and move the locking lever out of the line of movement of shoulder 66 before said shoulder reaches the end of the locking lever, so that the cam rings can be actuated a sufficient distance to eject a cup. In this clockwise movement of the cam rings 44 and 48, the high points on the cam ring 48 will first engage the rollers 45^a on fingers 45, and advance said fingers together with ejecting levers 49 between the flanges 40 of the lowermost cup 37 and the next cup. In the further rotation of the cam rings, the low points of cam ring 44 will be moved opposite the rollers 41^a on fingers 41 and permit said fingers to be withdrawn from under the flange on the lowermost cup by the springs 43. The cams 53 in the further movement of the cam rings 44 and 48 will pass under rollers 52, rock said levers and as the inner ends thereof are between the flanges 40 of the two lowermost cups, the lowermost cup will be ejected by said levers while the second cup, together with the remainder of the cups, will be supported by the fingers 45. The hand lever 61 is now released and as the coin has been moved beyond the free end of plate 59, it will drop through the slot in the hand lever and per-

mit the spring 57 to move the locking lever 55 into locking position and the cam rings will be returned to the positions shown in the drawings, by springs 54.

If it is desired to provide ejecting mechanism without the use of a coin, it is only necessary to omit lever 55, and in which case the mechanism can readily be actuated to eject cups one by one.

The advantages of my invention result from the provision of cup dispensing mechanism having a plurality of ejectors which are arranged to move in planes substantially parallel to the axis of the cup to be ejected, so as to move the cup in a direct line.

Another advantage results from the provision of radially movable cup holding fingers carrying cup ejectors which are so arranged that the fingers are first moved into position to hold the second cup while the ejectors engage the first cup to strip it from the second cup. This provision of radially movable fingers also permits the provision of fingers and ejectors having broad bearing surfaces, as well as permitting the engagement of the cup flanges at or near their junctions to the cup bodies. The expression "radially movable fingers" means that said fingers are movable toward and from the common axis of the supporting frame, cup-container, and cups.

This application is a division of my application, Serial No. 312,806, filed July 23, 1919.

Having now fully described my invention, what I claim and desire to protect by Letters Patent is—

1. A cup dispensing device having cup supports arranged at different angular positions about the cup delivery point and also arranged to be moved into and out of holding relation with the first and second cups by a right-line movement radial to the axis of the cups; a cup ejector distinct from the cup supports and mounted on an axis perpendicular to the axis of the cups; means for moving the cup supports; and means for rocking the cup ejector about its pivot axis when the support for the first cup is withdrawn and the other support is in supporting relation to the second cup.

2. Cup ejecting mechanism for stacked conical cups having flanges at their open ends, comprising alternately operable, radially movable supports for engaging respectively the flanges of the first and of the second cups; cam means for moving said supports in a right line toward the axis of the cups; means for moving said supports in the reverse direction; cup ejectors mounted upon the several supports for the second cup and adapted to swing in a plane radial to the axis of the cups; and cam means for actuating the ejectors to eject the

first cup when the flange of the second cup is engaged by the supports.

3. Cup dispensing mechanism for stacked conical cups having flanges at their open ends, comprising radially movable fingers for supportingly engaging the flange of the first cup; radially movable fingers for supportingly engaging the flange of the second cup; means for moving said fingers radially inward in alternation; means for moving said fingers radially outward in alternation; cup ejecting devices for engaging the flange of the first cup; and means for actuating the ejectors to eject the first cup when one set of fingers is withdrawn and the other set is in supporting relation with the second cup.

4. A cup-dispensing device comprising a supporting frame; upper and lower sets of fingers radially movable in said frame, for supporting a stack of nested, flanged, conical cups, the upper set of fingers being arranged to be moved into position to engage the flange of the second cup when the lower set is withdrawn, and the lower set being arranged to be moved into position to engage the flange of the first cup when the upper set of fingers is withdrawn; oscillating cam means for moving said fingers radially inward; means for moving said fingers radially outward; cup ejectors arranged to engage the flange of the first cup to eject said cup when the fingers of the upper set are in position to support the second cup; and cams to actuate said ejectors.

5. A cup-dispensing device comprising a supporting frame; upper and lower sets of fingers radially movable in the frame, for supporting a stack of flanged and nested conical cups, the upper set of fingers being arranged to be moved into position to engage the flange of the second cup when the lower set is withdrawn, and the lower set being arranged to be moved into position to engage the flange of the first cup when the upper set of fingers is withdrawn; oscillating cam means for moving said fingers radially inward; means for moving said fingers radially outward; cup ejectors arranged to be moved in planes parallel to the axis of the cups; and means for actuating the ejectors to strip the first cup from the second cup when the lower set of fingers is retracted and the upper set is advanced into supporting position with relation to the second cup.

6. A device for dispensing stacked conical cups having flanges at their tops, comprising a frame, upper and lower sets of radially movable fingers mounted on the frame, an oscillating cam ring mounted on the frame, cams for said ring for advancing one set of fingers and to then permit the other set to be withdrawn, means for withdrawing said fingers, rocking ejectors arranged to be moved about axes perpendicular to the axis of the cups, and cams on the cam ring to

rock the ejectors to eject the first cup when the lower set of fingers is withdrawn and the upper set is advanced, to strip the first cup from the second cup along the axis of the cups.

7. A device for dispensing stacked conical cups having flanges at their tops, comprising a frame, upper and lower sets of radially movable fingers mounted on the frame, an oscillating cam ring mounted on the frame, cams on said ring for advancing one set of fingers and to then permit the other set to be withdrawn, springs for withdrawing said fingers, a rocking ejector carried by each of the upper fingers and arranged to be moved about axes perpendicular to the axis of the cups, and cams on the cam ring to rock the ejectors to eject the first cup when the lower set of fingers is withdrawn and the upper set is advanced, to strip the first cup from the second cup along the axis of the cups.

8. Mechanism for dispensing stacked flanged conical cups, comprising a frame; upper and lower sets of fingers movable in lines radial to the common axis of the frame and cups, the lower set of fingers being arranged to move beneath the lowermost flange of the stacked cups to support the column, the upper set of said fingers being arranged to move between the lowermost flange and the one next above it to support the column of cups when the lower fingers are withdrawn to release the lowermost cup; means for advancing the upper and lower fingers into supporting position alternately; means for alternately retracting said fingers from supporting position; cup ejectors carried by the upper fingers and movable into ejecting relation to the lower cup when the upper fingers are carried into cup-supporting position; and means for rocking the ejectors relatively to the upper set of fingers when the latter are in supporting position, to positively withdraw the lowermost cup from the second cup.

9. A cup dispensing device comprising a supporting frame having an opening through it for the passage of cups, means carried by said frame for holding in upright position a column of flanged cups in nested relation, a plurality of guideways carried by the frame and arranged in radial relation to the axis of the cup column, an upper and a lower cup support in each radial guideway, a cup ejector carried by each upper cup support, on a horizontal pivot, an oscillatable ring concentric with the cup column and supported by the frame, said ring being provided with cam surfaces to move inward and hold in cup-supporting adjustment, alternately, the upper and lower cup supports, and with other cam surfaces to actuate the cup ejectors when the upper cup supports are in supporting position and the lower cup

supports are in retracted position, and means for moving the cup supports in a direction opposite to that in which they are moved by said cam surfaces.

5 10. A cup dispensing device comprising a frame having an opening for the passage through it of cups, means carried by said frame for holding in upright position a column of flanged cups in nested relation, a 10 plurality of guideways carried by said frame and arranged in radial relation to the axis of the cup column, a cup support movable in each radial guideway, cup ejectors carried one by each said cup support upon a horizontal pivot, means for moving said cup supports to a position where their supporting ends shall enter between the lowermost cup of the column and the cup next above it, and means for rocking said ejectors each in 15 a vertical plane radial to the axis of the cup column.

11. In a machine for dispensing flanged cups, a base having a central opening for the passage of cups; a slide on said base 25 reciprocable toward and away from said central opening; another slide also on said base and spaced above the first-mentioned slide; and means carried by said base for advancing and receding the respective slides.

30 12. In a dispensing mechanism for flanged cups, a base having a central opening for the passage of cups; a series of slides on said base reciprocable toward and away from said central opening; another series of slides 35 also on said base and spaced above the first-mentioned series; and means carried by said base for advancing and receding the slides of the respective series.

13. In a dispensing mechanism for flanged 40 cups, a base having a central opening for the passage of cups; a series of slides on said base reciprocable toward and away from said central opening; another series of slides also on said base and spaced above the first-mentioned series; means carried by said base 45 for advancing and receding the slides of

the respective series, each slide of the second-mentioned series having an ejector arm pivoted thereon; and means for operating each of said arms to cause the same to eject 50 a cup.

14. In a dispensing mechanism for flanged cups, a base having a central opening for the passage of cups; a series of slides on said base reciprocable toward and away from 55 said central opening; another series of slides also on said base and spaced above the first-mentioned series; and means carried by said base for alternately advancing and receding the slides of the respective series. 60

15. In a dispensing mechanism for flanged cups, a base having a central opening for the passage of cups; a series of movable cup supports on said base; an ejector distinct from the cup supports and pivotally supported in operative relation with respect to said supports; and means supported on said base for moving said cup supports and rocking said ejector about its pivot axis. 65

16. In a dispensing mechanism for flanged 70 cups, a base having a central opening for the passage of cups; a series of movable cup supports on said base; an ejector distinct from the cup supports and pivotally supported on said cup supports; and means 75 supported on said base for moving said cup supports and rocking said ejector about its pivot axis.

17. In a dispensing mechanism for flanged cups, a base having a central opening for 80 the passage of cups; a series of slides on said base reciprocable toward and away from said central opening; another series of slides also on said base and spaced above the first-mentioned series; and cams carried by said 85 base for advancing and receding the slides of the respective series.

In testimony of which invention, I have hereunto set my hand, at Detroit, Michigan, on this 13th day of January, 1922.

JOHN FRICK.

- supports are in retracted position, and means for moving the cup supports in a direction opposite to that in which they are moved by said cam surfaces.
- 5 10. A cup dispensing device comprising a frame having an opening for the passage through it of cups, means carried by said frame for holding in upright position a column of flanged cups in nested relation, a 10 plurality of guideways carried by said frame and arranged in radial relation to the axis of the cup column, a cup support movable in each radial guideway, cup ejectors carried one by each said cup support upon a horizontal pivot, means for moving said cup supports to a position where their supporting ends shall enter between the lowermost cup of the column and the cup next above it, and means for rocking said ejectors each in 15 a vertical plane radial to the axis of the cup column.
11. In a machine for dispensing flanged cups, a base having a central opening for the passage of cups; a slide on said base reciprocable toward and away from said central opening; another slide also on said base and spaced above the first-mentioned slide; and means carried by said base for advancing and receding the respective slides.
- 30 12. In a dispensing mechanism for flanged cups, a base having a central opening for the passage of cups; a series of slides on said base reciprocable toward and away from said central opening; another series of slides 35 also on said base and spaced above the first mentioned series; and means carried by said base for advancing and receding the slides of the respective series.
13. In a dispensing mechanism for flanged 40 cups, a base having a central opening for the passage of cups; a series of slides on said base reciprocable toward and away from said central opening; another series of slides also on said base and spaced above the first-mentioned series; means carried by said base for advancing and receding the slides of
- the respective series, each slide of the second-mentioned series having an ejector arm pivoted thereon; and means for operating each of said arms to cause the same to eject 50 a cup.
14. In a dispensing mechanism for flanged cups, a base having a central opening for the passage of cups; a series of slides on said base reciprocable toward and away from 55 said central opening; another series of slides also on said base and spaced above the first-mentioned series; and means carried by said base for alternately advancing and receding the slides of the respective series.
15. In a dispensing mechanism for flanged cups, a base having a central opening for the passage of cups; a series of movable cup supports on said base; an ejector distinct from the cup supports and pivotally supported in operative relation with respect to said supports; and means supported on 60 said base for moving said cup supports and rocking said ejector about its pivot axis.
16. In a dispensing mechanism for flanged cups, a base having a central opening for the passage of cups; a series of movable cup supports on said base; an ejector distinct from the cup supports and pivotally supported on said cup supports; and means supported on said base for moving said cup supports and rocking said ejector about its 65 pivot axis.
17. In a dispensing mechanism for flanged cups, a base having a central opening for the passage of cups; a series of slides on said base reciprocable toward and away from said central opening; another series of slides also on said base and spaced above the first-mentioned series; and cams carried by said 70 base for advancing and receding the slides of the respective series.

In testimony of which invention, I have hereunto set my hand, at Detroit, Michigan, on this 13th day of January, 1922.

JOHN FRICK.

Certificate of Correction.

It is hereby certified that Letters Patent No. 1,593,717, granted July 27, 1926, upon the application of John Frick, of Detroit, Michigan, for an improvement in "Cup-Dispensing Apparatus," were erroneously issued to the inventor, said Frick, whereas said Letters Patent should have been issued to *Richmond Beverage Machine Corporation, of Richmond, Virginia, a corporation of Virginia*, said corporation being assignee, by *mesne assignments*, of the entire interest in said invention, as shown by the records of assignments in this office; and that the said Letters Patent should be read with this correction therein that the same may conform to the record of the case in the Patent Office.

Signed and sealed this 28th day of September, A. D. 1926.
